UNITED STATES PATENT OFFICE.

WILLIAM C. HOMAN, OF MERIDEN, CONNECTICUT, ASSIGNOR TO THE EDWARD MILLER & COMPANY, OF SAME PLACE.

WICK-RAISER FOR CENTRAL-DRAFT LAMPS.

SPECIFICATION forming part of Letters Patent No. 477,863, dated June 28, 1892.

Application filed November 30, 1891. Serial No. 413,574. (No model.)

To all whom it may concern:

Be it known that I, WILLIAM C. HOMAN, of Meriden, in the county of New Haven and State of Connecticut, have invented a new 5 Improvement in Wick-Adjusters for Central-Draft Lamps; and I do hereby declare the following, when taken in connection with accompanying drawings and the letters of reference marked thereon, to be a full, clear, and 10 exact description of the same, and which said drawings constitute part of this specification, and represent, in—

Figure 1, a view, partly in side elevation and partly in vertical section, of a lamp constructed in accordance with my invention; 15 Fig. 2, a detached view in side elevation of the wick-band and adjusting-bar; Fig. 3, a detached sectional view of the long screw-threaded sleeve, to the lower end whereof the 20 operating-nut is attached.

My invention relates to an improvement in wick-adjusters for central-draft lamps, the object being to produce a simple, durable, effective, and convenient device adapted for 25 direct manual operation through its upper end or operation by a nut through its lower end, as found most convenient.

With these ends in view my invention consists in a wick-adjuster having certain details 30 of construction and combinations of parts, as will be hereinafter described, and pointed out in the claims.

The fount A and central draft-tube B of the lamp are of ordinary construction, except 35 that the former has mounted in it at a point to one side of the said tube a vertical bearing-tube C, which passes through the oil-chamber and projects a very little out of the fount at its upper and lower ends, at which points 40 it is soldered or otherwise sealed, so as to prevent any escape of oil from the fount. A long internally-threaded sleeve D is located within the said bearing-tube, extending nearly 45 to the upper end thereof and constructed at its lower end with a neck D', which passes through the contracted lower end of the tube and receives the centrally-perforated operating-nut E, which is rigidly secured to the said neck. A shoulder d, formed between the 50 lower end of the said sleeve D and its neck D', rests upon the contracted lower end of

the bearing-tube and prevents the downward movement of the sleeve, while the inner end of the nut engages with the extreme end of the bearing-tube and prevents the upward 55 movement of the sleeve, whereby the same is held against longitudinal movement in either direction, but is free to rotate. The wick-band F, encircling the draft-tube B, is of ordinary construction, and has connected with 60 it the bent lower end of the short leg G of the bowed adjusting-bar, the said leg playing up and down through an open slot H, extending outwardly from the inner edge of the top of the lamp-fount. The long leg G' 65 of the said adjusting-bar, which is preferably formed from a heavy rod or wire, is straight and extends down through the threaded sleeve D, before mentioned, through the centrally-perforated operating-nut E, at 70 attached to the lower end thereof, and projects below the said nut, its projecting lower end being threaded to receive the retaining-button I, which has the twofold function of preventing the said leg of the bar from being 75 drawn out of the bearing-tube and threaded sleeve and of affording a means for raising and lowering the bar by direct or plunging action through the lower end of its said leg. The long vertical loop formed by the upper 80 portions of the said legs of the bowed adjusting-bar forms a handle for grasping the same for direct manual operation from the top of the lamp-fount. The said long leg G' of the bar is provided about midway of its length 85 and, as herein shown, slightly above its longitudinal center with a double spiral thread J, the same being formed upon the surface of a short sleeve J', fixed upon the bar. As herein shown, the said double screw-thread contains about two turns and is of very coarse 90 pitch, in which it corresponds to the pitch of the thread D² of the sleeve D, the said thread D² consisting, as herein shown, of a rectangular wire formed into a coarse spiral and secured to the inner face of the sleeve, which may, however, if desired, have the thread formed in it by an obvious process analogous to beading; but however the threads of the 95 bar and sleeve are formed it is designed that they shall be so coarse in pitch as to permit the bar to be raised and lowered by taking 100

- hold of the long loop at its upper end and by taking hold of the knob I, attached to its lower end. In such operation of the bar the sleeve and its nut would be rotated in one direction 5 or the other, according to the way in which the bar was moved, the friction of the described rotation of the sleeve being reduced to the minimum by contracting its lower end to form the neck D' and shoulder d, the latter resting upon the contracted lower end of the bearing-tube C. The object of making the threads very coarse is of course to reduce the friction of their operation and permit the bar to be plunged, so to speak, up and down.
- 15 I do not limit myself to the use of double threads J on the bar; but threads so constructed reduce the wear and friction of operation greatly.

To operate the bar from its lower end by 20 the nut E, the same is grasped between the fingers and turned, whereby the bar is operated directly through the sleeve. To remove the bar, the retaining-button I is taken off, after which the bar and the wick-band may 25 be drawn out of the lamp integral or without dismemberment, the sleeve and nut remaining in their normal positions.

I would have it understood that I do not limit myself to the exact construction herein 30 shown and described, but hold myself at liberty to make such changes and alterations as fairly fall within the spirit and scope of my invention.

I am aware that it is old to provide a lamp- 35 fount at a point to one side of its center with a vertical bearing-tube to contain an internally-threaded rotatable but longitudinally-immovable sleeve receiving the long leg of a wick-adjuster and furnished at its lower 40 end with a nut by which it is rotated to move the said wick-adjuster up and down by screw action; and I do not, therefore, claim that construction, broadly.

Having fully described my invention, what 45 I claim as new, and desire to secure by Letters Patent, is—

1. In a central-draft lamp, the combination, with the fount and draft-tube thereof, of a bearing-tube mounted in the fount to one side 50 of the said draft-tube and projecting at its upper and lower ends through the fount, a long rotatable sleeve having an internal

thread located within the said tube, in which it is held against longitudinal movement, a centrally-perforated operating-nut rigidly 55 connected with the lower end of the sleeve, a wick-band encircling the draft-tube, a bowed adjusting-bar having its short leg attached to the said band and its long leg passed downward through the said sleeve, through the 60 centrally-perforated nut connected with the lower end thereof, and provided with a coarse thread taking into the internal thread of the sleeve, and a removable retaining-button attached to the projecting lower end of the long 65 leg of the said bar, the threads of the sleeve and bar being constructed so coarse in pitch as to permit the bar to be vertically reciprocated manually by direct or plunging movement from its upper and its lower end, sub- 70 stantially as set forth.

2. In a central-draft lamp, the combination, with the fount and draft-tube thereof, of a bearing-tube mounted in the fount to one side of the draft-tube and projecting at its open 75 upper and lower ends from the fount, a long internally-screw-threaded rotary sleeve located within the said tube and constructed at its lower end with a neck which projects from the lower end of the bearing-tube, a centrally-perforated nut attached to the said neck at the lower end of the sleeve, a wick-band encircling the draft-tube, a bowed adjusting-bar having a short leg and a long leg, the former being attached to the said band and 80 the latter being passed downward through the said sleeve projecting through the centrally-perforated nut at the lower end thereof and provided with a coarsely-pitched double thread co-operating with the internal thread 85 of the sleeve, and a retaining-button removably attached to the said projecting lower end of the long leg of the bar, the threads of the sleeve and bar being so coarsely pitched as to permit the same to be operated manually by 90 direct or plunging movement from its upper and its lower end, substantially as described.

In testimony whereof I have signed this specification in the presence of two subscribing witnesses.

WILLIAM C. HOMAN.
